UNITED STATES PATENT OFFICE.

PAUL C. GALLAGHER, OF OMAHA, NEBRASKA, ASSIGNOR TO PAXTON AND GALLAGHER COMPANY, OF OMAHA, NEBRASKA.

DESIGN FOR A BOTTLE.

Application filed June 13, 1925. Serial No. 13,776. Term of patent 14 years.

To all whom it may concern:

Be it known that I, PAUL C. GALLAGHER, a citizen of the United States, residing at 513 South 38th Street, Omaha, county of Douglas, and State of Nebraska, have invented a new, original, and ornamental Design for Bottles, of which the following is a specification, reference being had to the accompanying drawing, forming part thereof.

I claim:—

The ornamental design for a bottle, as shown.

PAUL C. GALLAGHER.
